UNITED STATES PATENT OFFICE.

CHARLES J. STROSACKER AND HOWARD J. RUPRIGHT, OF MIDLAND, MICHIGAN,
ASSIGNORS TO THE DOW CHEMICAL COMPANY, OF MIDLAND, MICHIGAN, A COR-
PORATION OF MICHIGAN.

METHOD OF MAKING BROMINATED INDIGOS.

Application filed September 1, 1920. Serial No. 407,523.

To all whom it may concern:

Be it known that we, CHARLES J. STROSACKER and HOWARD J. RUPRIGHT, citizens of the United States, and residents of Midland, county of Midland, State of Michigan, have jointly invented a new and useful Improvement in Methods of Making Brominated Indigoes, of which the following is a specification, the principle of the invention 10 being herein explained and the best mode in which we have contemplated applying that principle, so as to distinguish it from other inventions.

The bromination of indigo, especially 15 where the higher bromine substitution products are desired, has always heretofore been regarded as presenting peculiar difficulties or at least has so been represented, particularly in the patent literature. Thus, it has 20 always apparently been regarded as essential that a particular diluent or vehicle, either neutral or acid, be employed in which to carry on the reaction between the original indigo and the bromine, as well as to use 25 elevated temperatures or pressures, or both. The present reference is to the direct bromination of indigo in contradistinction to the introduction of the halogen in nuclei or radicals from which the indigo is subsequently synthetically prepared.

In contradistinction to the prevailing difficult and involved methods, we have discovered that it is possible to directly react upon the dry indigo with bromine at atmospheric 35 pressure and at a temperature not above 80 or 90° C., all of the known bromine substitution products i. e. mono-, di-, tri-, tetra-, penta- and hexa-brom indigo being readily prepared by this method and with equal ease 40 and facility, the only difference in requirements for obtaining the different derivatives being the proper proportioning of the amount of bromine utilized. The invention accordingly consists of the steps hereinafter 45 fully described and particularly pointed out in the claims, it being understood that the annexed drawing and following description illustrate merely one of the several ways in which the invention may be embodied.

50 In said annexed drawing:—

The single figure there appearing is a diagrammatic representation of an apparatus suitable for the carrying out of our present improved method of brominating indigo.

As shown in the drawing in question, the 55 reaction chamber 1 consists of an ordinary sheet steel tumbler revolving upon trunnions 2 and 3 and containing a number of iron balls 4, said tumbler being jacketed to permit the circulation of hot water or other 60 heating medium around the same. Such heating medium is designed to be supplied through connections 6 leading through the trunnion 2. In view of the moderate temperatures required, as hereinafter set forth, 65 such heating may be accomplished by simply revolving the tumbler in a more or less open water bath.

The tumbler is provided in its side with a manhole opening 7 having a suitable closure, through which opening the dry indigo may be charged. Said tumbler also is provided with a connection 8 through trunnion 3, through which liquid bromine may be similarly supplied to its interior. Connected with the interior of the tumbler through this same trunnion 3 is a reflux condenser 9 of usual construction, connected at its discharge end with an absorber 10 adapted to contain caustic soda for the purpose presently to be described.

In the operation of the foregoing apparatus to carry on our improved method of brominating indigo, the dry indigo as already indicated, is charged into the tumbler 85 through the opening 7, the latter closed and the tumbler then revolved for a short time, as a result of which the indigo is more or less finely pulverized by the action of the balls 4. Thereupon the liquid bromine is 90 started in through the connection provided for the purpose, the total charge being added at the start and as speedily as possible. Then the charge is heated up as fast as the reaction will permit (no pressure being allowed to build up in the reaction chamber or tumbler) until a temperature of 50° to 60° C. is obtained, such temperatures referring to the water bath or circulating liquid whereby the tumbler is heated. The gas 100 coming from the tumbler passes through the reflux condenser which serves to return to said tumbler the bromine driven off, while the hydrobromic acid formed as a result of the reaction goes on to be absorbed in the 105 caustic soda in the absorber.

It will be understood that during the operation just described the tumbler continues

to be revolved, the above mentioned temperature being maintained from 6 to 7 hours, being increased gradually in the latter portion of such period from 60° to 80° C. 5 and then carried up to 90° C., where it is held for from 7 to 9 hours longer.

The foregoing procedure obtains whichever of the substitutions it is desired to make, the degree of substitution being controlled by the amount of bromide added. The ratio of bromine charged, in order to produce mono-, di-, tri-, tetra-, penta- or hexa-brom indigo is respectively 0.7, 1.4, 10 2.0, 5.0, 7.0, and 8.0 parts by weight of liquid bromine per one part of dry indigo.

After the reaction is complete, the charge is neutralized as rapidly as possible with dilute caustic soda, care being taken to keep the charge slightly acid throughout the neutralizing period, the rotation of the tumbler being continued during this stage until the charge is thoroughly uniform and ground off from the sides of the tumbler. Sodium bisulphite is then added and the grinding continued at room temperature for several 20 hours, whereby all of the bromine combined with the product in an unstable form is removed and the product itself at the same time is ground to a very high degree of 25 fineness.

The charge is finally transferred to a suitable container and given a strong acid boil with hydrochloric acid for several hours, after which the product is filtered, washed 30 with water and made up to the customary percentage paste for the trade, or else formed in cakes or dried to form a powder, as the case may be. The bromine recovered in the absorber as sodium bromide may be reconverted into liquid bromine for further use, and since we are able to thus recover over 40 90% of that portion of the original charge of bromine not combined with the product, it will be evident that a high degree of economy is effected in this respect. We also obtain by the process as described above efficiencies in the case of each product named of above 90% based upon the dry indigo charged.

50 Other modes of applying the principle of our invention may be employed instead of the one explained, change being made as regards the method herein disclosed, provided the step or steps stated by any of the 55 following claims or the equivalent of such stated step or steps be employed.

We therefore particularly point out and distinctly claim as our invention:—

1. The method of brominating indigo, 60 which consists in reacting directly on the same, dry, in the absence of any diluent or other reagent, with bromine in amount from 15% to 25% in excess of the theoretical to form the desired substitution product, the 65 reaction being carried on at a temperature of

from 50° to 90° C. and under approximately atmospheric pressure.

2. The method of brominating indigo, which consists in reacting directly on the same, dry, in the absence of any diluent or other reagent, with bromine in amount from 15% to 25% in excess of the theoretical to form a mono-brom to hexa-brom substitution product as desired, the reaction being carried on initially at a temperature of from 70 50° to 60° C. and then gradually increased to approximately 90° C. all under approximately atmospheric pressure.

3. The method of brominating indigo, which consists in reacting directly on the 80 same, dry, in the absence of any diluent or other reagent, with bromine in amount from 15% to 25% in excess of the theoretical to form a mono-brom to hexa-brom substitution product as desired, the reaction being 85 carried on for six to seven hours at from 50° to 60° C., then gradually increased to approximately 90°, such last mentioned temperature being maintained for seven to nine hours, all under approximately atmospheric 90 pressure.

4. In a method of brominating indigo, the steps which consist in adding directly to the same, in dry finely ground condition and in the absence of any diluent or other reagent, a quantity of liquid bromine in amount from 15 per cent to 25 per cent in excess of the theoretical to form the desired substitution product, grinding together the two ingredients, and gradually heating the 95 resulting mixture to a temperature of from 50° to 60° C., all under approximately atmospheric pressure.

5. In a method of brominating indigo, the steps which consist in adding directly to the same, in dry finely ground condition and in the absence of any diluent or other reagent, a quantity of liquid bromine in amount from 15 per cent to 25 per cent in excess of the theoretical to form the desired 100 substitution product, grinding together the two ingredients, and heating the resulting mixture as fast as the reaction will permit first to from 50° to 60° C. and then to approximately 90° C.

6. In a method of brominating indigo, the steps which consist in adding directly to the same, in dry finely ground condition and in the absence of any diluent or other reagent, a quantity of liquid bromine in amount from 120 15 per cent to 25 per cent in excess of the theoretical to form the desired substitution product, the total quantity of bromine being added at once, grinding together the two ingredients and gradually heating the resulting mixture to a temperature of from 50° to 90° C., all under approximately atmospheric pressure.

7. In a method of brominating indigo, the steps which consist in adding directly to the 130

same, in dry finely ground condition and in the absence of any diluent or other reagent, a quantity of liquid bromine in amount from 15 per cent to 25 per cent in excess of the theoretical to form the desired substitution product, the total quantity of bromine being added at once, grinding together the two ingredients, and heating the resulting mixture as fast as the reaction will permit first to from 50° to 60° C. and then to approximately 90° C.

8. In a method of brominating indigo, the steps which consist in adding directly to the same, in dry finely ground condition and in the absence of any diluent or other reagent, a quantity of liquid bromine in amount from 15 per cent to 25 per cent in excess of the theoretical to form the desired substitution product, the total quantity of bromine being added at once, grinding together the two ingredients, and heating the resulting mixture as fast as the reaction will permit first to from 50° to 60° C., then to approximately 90° C., neutralizing the charge with caustic soda, and then adding sodium bisulphite, the grinding being continued during the two last-named steps.

9. In a method of brominating indigo, the steps which consist in adding directly to the same, in dry finely ground condition and in the absence of any diluent or other reagent, a quantity of liquid bromine in amount from 15 per cent to 25 per cent in excess of the theoretical to form the desired substitution product, the total quantity of bromine being added at once, grinding together the two ingredients, and heating the resulting mixture as fast as the reaction will permit first to from 50° to 60° C., then to approximately 90° C., neutralizing the charge with caustic soda, and then adding sodium bisulphite, the grinding being continued during the two last-named steps.

Signed by us, this 2nd day of August, 1920.

CHARLES J. STROSACKER.
HOWARD J. RUPRIGHT.
